UNITED STATES PATENT OFFICE.

HENRI GILLOU, OF MONTROUGE, FRANCE.

BELT-DRIVING DEVICE FOR RAILWAY-CARRIAGE DYNAMOS.

Application filed January 28, 1925, Serial No. 5,384, and in France January 28, 1924.

This invention relates to an improved belt driving device for dynamos installed on the trucks of railway or tramway cars and adapted to furnish the electric current required for the lighting of such cars or for other purposes.

In the lighting devices of this type which have been hitherto constructed and used, the dynamo has been connected to the truck by means of hinges and it has been so arranged as to have its axis of rotation at right angles to the track, i. e. to the direction in which the car travels. In such devices the dynamo has driven directly through a driving belt from a pulley mounted on one axle of the car. The tension of said belt has been obtained either merely by the effect of the horizontal force component resulting from the weight of the dynamo which is hinged at a point spaced from its center of gravity, or else by the action of a spring whose force could be regulated. Such devices have had the two following disadvantages:—First, the suspension of the dynamo in the first mentioned position caused excessive variations of tension on the belt when the speed of the car was suddenly increased or decreased owing to the inertia of the dynamo. The belt was thus subjected to great stresses, and it often was either torn off or so loosened that it dropped from the pulley, even if the latter was provided with flanges. Secondly, whenever the car traveled on a curve of the track, the driving axle assumed an angular position with respect to the axis of rotation of the dynamo either in one direction or another, the angle thus formed generally being from 6° to 10° , whereby, inasmuch as a transmission belt connecting non-parallel shafts can only operate properly if its driving side always remains in a perpendicular plane to the shaft carrying the corresponding pulley, the operation of the belt was often unsatisfactory.

According to the present invention a belt driving device for railway or tramway car dynamos is provided which entirely obviates the aforesaid disadvantages.

Briefly stated, this device is characterized by the fact that the dynamo mounted on hinges (as in prior devices) is so arranged that its axis of rotation is maintained in constant parallelism to the track, i. e. to the direction of travel of the carriage, this re-

sult being secured by means of two guide rollers which guide the belt and are so disposed that their peripheries are in tangential relation to the two median transverse and longitudinal planes respectively of the pulleys of the axle and dynamo when in normal position and because the axis of rotation of the dynamo would, if extended intersect the axis of rotation of the driving axle.

In the accompanying drawing:—

Figure 1 is a diagrammatic longitudinal elevational view of the device showing how it is suspended underneath the girders of the car.

Figure 2 is a diagrammatic plan view of the said device illustrating in broken lines the respective positions assumed by the driving axle, driving pulley and belt when the car travels on curves of the track.

A designates the axis on which the dynamo D is hinged or suspended underneath the frame of the car, said car having frame girders L; B designates the axis of revolution of the rotor of said dynamo. The said axis, if prolonged would intersect the axis of rotation of the driving axle E. As represented, the belt C passes over the driven convex pulley P mounted on and turning with the shaft of the dynamo. Said belt C then passes over guide-rollers G, G' laterally located above and below said pulley P and it finally passes over a driving pulley or drum T secured to the driving axle E. The median planes of said pulleys P and T are tangential to the surfaces of rollers G, G'. It is clear that, owing to the guiding action of the two rollers G, G', the driving and driven sides of the belt will respectively engage the pulleys P and T constantly and irrespective of the varying inclinations between the driving axle and the dynamo shaft whenever the car travels on a curve of the track, whereby all risks of the said belt being torn off or dropping from the pulley P will be obviated. Moreover, all the objectionable variations in the tension of the belt because of the inertia of the dynamo are eliminated, and the required tension of the belt is nevertheless ensured by the offset weight of suspension of the dynamo so that it is downwardly forced by gravity so as to tense the belt.

As illustrated diagrammatically in Figure 2, whenever the car travels on a curve the axis of rotation of the driving axle E will as-

sume different positions as shown in broken lines, and this will cause the belt to correspondingly assume the respective positions shown in broken lines. The rollers G, G' will guide the belt in the various positions thereof so that its driving and driven sides will constantly engage the pulley P at right angles to its axis of rotation.

The rollers G and G' are mounted in any suitable manner upon the frame of the car, independently of the trucks, the axes g and g' of said rollers G and G' being substantially vertical. Hence, when the trucks are turned, so that the axle E is turned around a vertical line, the tension, position and driving force of the first belt section intermediate pulley T and rollers G, G' are not substantially changed, and the position and driving force of the second belt section intermediate the rollers G, G' and dynamo pulley P are not changed. As I claim that my invention is broadly new, I do not wish to limit myself to a construction in which the shafts of rollers G, G' are exactly vertical, and in which the axis of the dynamo rotor is exactly aligned with the longitudinal axis of the car, since it is within the limits of my invention if the arrangement and location of the parts before specified is substantially followed to an extent sufficient to maintain a drive of the dynamo sufficiently uniform for practical purposes when the speed of the car is increased or decreased, or if the car travels in a curved path. The rollers G and G' may be considered as secondary driving means for the dynamo, said secondary driving means being operated by the revolution of the axle.

In accordance with the patent statutes, a preferred embodiment of the invention has been described in the foregoing specification but it will be appreciated that modifications might be made therein without departing from the spirit and scope of the invention.

What I claim and desire to secure by Letters Patent is:—

1. In a drive for a dynamo connected to a railroad car or the like having trucks, the combination of means for connecting said dynamo to said car independently of said trucks, secondary revoluble driving means for said dynamo spaced from the shaft of said dynamo, said secondary revoluble driving means being supported from said car independently of said trucks, primary revoluble driving means mounted on a truck and connected to and adapted to operate said secondary driving means, said secondary driving means being wholly free from any connection with said trucks save for their connection with said primary driving means, the respective axes of revolution

of said primary driving means and of said secondary driving means being non-parallel.

2. In a drive for a dynamo connected to a railroad car or the like having trucks, the combination of means for connecting said dynamo to said car independently of said trucks, secondary pulley means supported from said car wholly independently of said trucks and mounted to revolve about a substantially vertical axis, and primary pulley means actuated by the revolution of the axle of one of said trucks and connected to the secondary pulley means by a belt, said secondary pulley means being free from the shaft of said dynamo and being connected to said shaft.

3. A drive for a dynamo connected to a railroad car or the like having trucks, comprising means for pivotally suspending said dynamo from the said car independently of said trucks and on a line substantially parallel to the longitudinal axis of said car, said dynamo having a pulley, two guide rollers connected to said car independently of said trucks and adapted to turn around substantially vertical axes, both said rollers being laterally located with respect to the dynamo pulley and on the same side thereof, one of said rollers being located higher than said pulley and the other being located lower than said pulley, and a drive pulley located on the axle of one of said trucks, the said drive pulley and rollers and dynamo pulley being adapted to support a single endless belt.

4. A drive according to claim 3 in which the axis of revolution of the dynamo pulley substantially intersects the axis of the said axle.

5. A drive according to claim 3 in which the central longitudinal plane of the dynamo pulley is substantially tangential to the periphery of the said rollers.

6. In combination with a railroad car or the like having trucks, a dynamo, means adapted to pivotally suspend said dynamo from said car independent of the trucks thereof so that said dynamo can swing on a line making an angle less than ninety degrees with the longitudinal axis of the car, a primary driving pulley on one of said trucks and adapted to be revolved by the revolution of the axle of said truck, and an endless belt drive intermediate said primary driving pulley and the shaft of said dynamo, said endless belt drive including idler guide means connected to said car independently of said trucks.

In testimony whereof I have signed my name to this specification.

HENRI GUILLOU.

Certificate of Correction.

Patent No. 1,622,315.

Granted March 29, 1927, to

HENRI GUILLOU.

It is hereby certified that error appears in the above-numbered patent requiring correction as follows: In the heading to the printed specification, line 3, name of patentee, for "Henri Guillou" read *Henri Guillou*; and that the said Letters Patent should be read with this correction therein that the same may conform to the record of the case in the Patent Office.

Signed and sealed this 19th day of July, A. D. 1927.

[SEAL.]

M. J. MOORE,
Acting Commissioner of Patents.
